US00D616282S

(12) **United States Design Patent**
Cosby et al.

(10) **Patent No.:** **US D616,282 S**
(45) **Date of Patent:** **** May 25, 2010**

(54) **HINGE**

(75) Inventors: **Scott Anthony Cosby**, North Curl Curl (AU); **Clive Solari**, East Lindfield (AU); **Jonathan James Creswell Lowe**, Doonside (AU); **Samuel John Deslandes**, Bondi Beach (AU)

(73) Assignee: **D&D Group Pty, Limited**, Brookvale, NSW (AU)

(**) Term: **14 Years**

(21) Appl. No.: **29/321,547**

(22) Filed: **Jul. 18, 2008**

(30) **Foreign Application Priority Data**

Jan. 23, 2008 (AU) 10277/2008

(51) **LOC (9) Cl.** **08-06**

(52) **U.S. Cl.** **D8/323**

(58) **Field of Classification Search** D8/355, D8/381, 323-330; 4/236, 240; D23/302; 16/309, 235, 275, 244, 379, 390, 430, 241, 16/238, 245, 236, 243, 242; 49/381

See application file for complete search history.
